ELECTRIC SWITCH COVER PLATE

Peter J. Hamill, 59 Bedford Place, Ramsey, N.J., and
Robert A. Ferguson, 95 Homewood Ave., Yonkers,
N.Y.

Filed July 10, 1961, Ser. No. 65,865

Term of patent 14 years

(Cl. D26—13)

FIG. 1 is a perspective view of an electric switch cover plate embodying our new design;

FIG. 2 is a front elevation thereof;

FIG. 3 is a side elevation thereof; and

FIG. 4 is a top plan view thereof.

We claim:

The ornamental design for an electric switch cover plate, as shown.
